[57] CLAIM

The ornamental design for a solar water heater or the like, as shown and described.

DESCRIPTION

FIG. 1 is a perspective view of a solar water heater or the like showing our new design as seen from the front and right side;

FIG. 2 is an enlarged top plan view thereof;

FIG. 3 is a bottom plan view thereof;

FIG. 4 is a front elevational view thereof; and

FIG. 5 is a rear perspective view thereof, on an enlarged scale.

The cross lines shown on the base of the device in FIGS. 1, 2, 3, and 4 are partially shown for ease of illustration and are understood to represent a conventional screen pattern.

FIG. 1.

FIG. 2.

FIG. 4.

FIG. 3.

FIG. 5.
